UNITED STATES PATENT OFFICE

GROVER C. WELTER, OF ROSWELL, NEW MEXICO

DESIGN FOR A NOVELTY SPUR

Application filed October 9, 1929. Serial No. 32,983. Term of patent 7 years.

To all whom it may concern:

Be it known that I, GROVER C. WELTER, a citizen of the United States, and a resident of Roswell, in the county of Chaves and State of New Mexico, have invented the new, original, and ornamental Design for Novelty Spur, of which the following is a specification.

Reference is had to the accompanying drawing, forming part thereof, wherein

spur showing my new design, a clamping strap being shown in connection therewith and indicated by dotted lines;

I claim:

The ornamental design for a novelty spur substantially as shown and described.

GROVER C. WELTER.
